UNITED STATES PATENT OFFICE

ROBERT H. MCCLINTIC, OF PITTSBURGH, PENNSYLVANIA, ASSIGNOR, BY MESNE ASSIGNMENTS, TO MCCLINTIC-MARSHALL CORPORATION, A CORPORATION OF PENNSYLVANIA

SPACING TABLE FOR MACHINES FOR PUNCHING BEAMS AND THE LIKE

Application filed November 15, 1930. Serial No. 495,852.

In the present practice the beam to be punched is held in a carriage or buggy which travels by intermittent movement along a spacing table or support, the carriage being caused to halt at the proper positions for the punching operations by means of stops engaged by the carriage and the stops being in turn retracted to permit the next advance of the carriage.

10. After the punching of the beam has been completed it is released from the carriage and lifted laterally off the spacing table.

The object which I have in view is the improvement of the spacing table whereby the placing of the stop members in operative position may be automatically accomplished and the stop members may be individually and automatically retracted from the path of the beam as the corresponding punching 20 operation is accomplished.

For this purpose I have devised the mechanism hereinafter described and claimed.

In the accompanying drawings, wherein I have illustrated a practical embodiment of 25 the principles of my invention, but which are not intended to limit the scope of the latter to the construction shown, Fig. 1 is a broken plan view of the beam-punch and the spacing table, two of my improved stop members 30 being shown in their operative position.

Fig. 2 is a broken side elevation of the same.

Fig. 3 is an enlarged section taken along the line 3—3 in Fig. 1, the stop member being 35 shown in its operative position in full lines and its position when retracted being indicated in part in dotted lines.

Fig. 4 is an enlarged detail partially in section taken along the line 4—4 in Fig. 3, the rock shaft being omitted.

Fig. 5 is a side elevation of the key block.

Fig. 6 is an end view of one of the stop members, the left end in Fig. 3.

45. Fig. 7 is a diagrammatic view showing the wiring of the motor which operates to retract the stop members individually.

Fig. 8 is a side elevation of a hand-operated stop member.

50. Fig. 9 is a plan view of the same.

Referring to the drawings the punch head is indicated in Fig. 1 at 1 in dotted lines. The horizontally disposed spacing table along which the beam to be punched is moved comprises a plurality of horizontally disposed rollers 2 arranged in spaced relation as indicated in Fig. 1. These rollers are mounted with their load supporting surfaces in the same horizontal plane.

Thus I have indicated a supporting frame 60 comprising the channel beams 3 on which are mounted the angle beams 4 and the ends of the rollers are journaled in suitable bearings in the angle beams. The angle beams 4 may be connected together at proper intervals by cross braces, such as 5. The channel beams 3 are supported on any suitable foundation.

Along one side of the spacing table a large I-girder 6 extends for which a suitable foundation is provided.

70. 7 represents a plurality of split bearings which are mounted on the girder 6 at suitable intervals, and 8 represents a horizontally disposed shaft journaled in said bearings for oscillation on its longitudinal axis.

75. The shaft is provided with a plurality of circumferentially disposed ribs 9 which are equally spaced apart and provide between them what may be termed annular grooves which are of the same width as the ribs. The ribs do not extend completely around the shaft 8 but are interrupted as at 10 in Fig. 1, the gaps being at what is the top of the shaft when the latter is at rest.

80. The front end of the shaft is provided with a collar 11 which bears against the front end bearing 7 while the other end of the shaft beyond the other end bearing 7 is provided with a collar 12 arranged to rotate in unison with the shaft. The shaft is thus prevented from longitudinal movement.

85. The collar 12 is provided with a radially disposed arm 13 and said arm is provided at its outer end with a split eccentric strap 14 which surrounds and rides on an eccentric disk 15 driven by the motor 16 through the speed reducer mechanism 17. It is obvious that when the motor 16 is in operation the shaft 8 is oscillated on its longitudinal axis.

90. 18 represents the stop members, two of 100

which are shown in Fig. 1. It will be understood that any required number of stop members are to be provided.

These stop members are in the form of metal bars disposed transversely of the spacing table and having at one end, the right end in Fig. 3, a half round socket 19 which is provided with circumferentially disposed ribs 20 of proper dimensions to fit in the grooves between the ribs 9 of the shaft 8, the grooves between the ribs 20 of the half-socket 19 being of proper dimensions to receive the ribs 9 of the shaft 8.

Thus the stop members 18 may be swung, with the shaft 8 as an axis, from their operative position shown in solid lines in Fig. 3 to their retracted position shown in dotted lines in Fig. 3, and vice versa, the interlacing of the ribs 9 and 20 however preventing a movement of the stop members longitudinally of the shaft 8.

The other or free ends of the stop members, that is the left end in Fig. 3, are provided with heads 21 having on their ends the spaced apart parallel ribs 22 with intervening grooves of equal width.

On the opposite side of the spacing table from the shaft 8 a horizontally disposed beam 23 is supported as by the brackets 24 from a girder 25, the beam being supported in the angular position shown in Fig. 3.

The beam 23 has one of its faces provided with transversely disposed parallel ribs 26 with intervening grooves of the same width, and the ribs 22 of the head 21 of the stop member 18 interlace with the ribs 26 of the beam 23 when the stop member is in its operative or horizontal position. Thus the stop member is held at both ends against the movement longitudinally of the spacing table.

When a beam is to be punched the operator determines from the blue print or other directions furnished him the position of the holes or groups of holes to be punched in the beam, and he then places the required number of stop members in proper position along the spacing table with their half sockets 19 engaging the shaft 8 and their heads 21 engaging the beam 23.

The beam to be punched indicated at 27 in Fig. 3 is introduced at the front end of the spacing table, that is the right end in Figs. 1 and 2, and is moved along the same until its front or forward end engages the first stop member 18. The punch head is then operated and by means of electrical mechanism hereinafter to be described the motor 16 is energized, causing the shaft 8 to oscillate moving first clockwise in Fig. 3 and then counter-clockwise, which oscillation, by means of connections hereinafter to be described, causes the stop member 18 which has been engaged by the front end of the beam 27 to be retracted into its raised position, so that the beam may thus be advanced further along

the table until it engages the next stop member and is positioned to be subjected to the next punching operation.

To enable a stop member 18 to be retracted by the oscillation of the shaft 8 I provide the half round socket member 19 with a key-way 28 in which is mounted the key 29 arranged for movement longitudinally of the shaft. The key moves in the interruptions 10 of the ribs 9 and the key is provided with ribs 30 and intervening grooves 31 of proper width so that when the key is in one position, that shown in Fig. 4, its ribs 30 will mate with the grooves of the shaft 8 so that the shaft 8 may be oscillated without swinging the stop member 18. However, when the key 29 is moved into its other position, that is from right to left in Fig. 4, its ribs 30 will mate with the ribs 9 of the shaft 8 so that when the shaft is oscillated the stop member will be swung with the shaft, that is raised to its retracted position indicated in dotted lines in Fig. 3.

The upper surface of the key 29 is provided with a trigger socket 32 in which is loosely seated the lower end of a trigger 33 which extends up through an opening in the half socket 19. The upper end of the trigger 33 is provided with an eye 34 which is fixed on the end of a rocker shaft 35. The rocker shaft 35 is journaled in brackets 36 extending upwardly from the stop member 18. The shaft 35 has fixed thereon the collars 37 of a pair of depending brackets 38 whose outer ends are secured to an impact plate 39 which is normally disposed a short distance in front of a shallow seat 40 in the front face of the stop member 18. The impact plate 39 is of the proper dimensions so that when pressed toward the stop member 18 it will retreat into the seat 40.

The helical spring 41 normally retains the impact plate 39 spaced forwardly from the stop 18 and returns the plate to such spaced relation when the pressure of the beam 27 is relieved therefrom. The spring 41 also acts to hold the key 29 in its retracted or inoperative position shown in Fig. 4 and to return it thereto when the pressure of beam 27 is relieved from the impact plate.

Thus when the forward end of the beam 27 engages the impact plate 39 of a stop member 18, the beam presses the impact plate 39 into the seat 40 and then comes to rest. The movement of the impact plate causes the key 29 to move into its operative position with its ribs 30 mating with the ribs 9 of the shaft 8 so that as the motor 16 is energized and the shaft 18 is rocked clockwise in Fig. 4 the stop member 18 is raised into its retracted position indicated in dotted lines in Fig. 3, thus permitting the beam 27 to be again advanced until its end engages and presses in the impact plate 39 of the next stop member 18. Means hereinafter to be described

are provided for latching a stop member in its retracted position and thus preventing the stop member from dropping down upon the beam.

The wiring and control circuits of the motor 16 are diagrammatically illustrated in Fig. 7. Thus 42 and 42' indicate the conductors of the line circuit and 43 and 44 the motor circuit. A magnetic switch 45 is arranged to connect the conductor 42 with the conductor 43 and the conductor 42' with the conductor 44. Such switch is operated by means of a solenoid 46 whose wire 47 is connected at one end to the conductor 42' and at its other end to a conductor 48 of a double control circuit. The other conductor 49 of said double control circuit is connected to the conductor 42. At either end of the double control circuit 48-49 I provide a limit switch. Thus the limit switch 50 is operated by the rocking lever 51 intermediately pivoted to a suitable support and the other end of the lever is held as by means of the spring 52 in contact with the frog-arm 53 of the clutch 54 of the punch head, the engaging of the clutch 54 causing the punch head to operate and its disengaging causing the cessation of the operation of the punch head, and the arrangement is such that when the clutch 54 is thrown in the switch 50 is closed and when the clutch is thrown out the switch 50 is opened. At the other end of the double control circuit I provide the contact switch 55 operated by a lever 56 pivotally connected to a suitable support intermediate of its ends. The lever 56 is held in resilient engagement as by a spring 57 with a cam 58 moving with the shaft 8 and which may be mounted on the collar 12. In Fig. 7 the shaft 8 is assumed to be at its position of rest and in that position the cam 58 holds the switch 55 open.

When the clutch 54 is thrown in by the operator to operate the punch head the switch 50 is closed, thus connecting up the solenoid conductor 47 in circuit with the supply conductors 42 and 42', and thus energizing the solenoid to close the magnetic switch 45. The closing of the switch 45 closes the motor circuit and causes the motor 16 to operate, thus causing the shaft 8 to turn on its longitudinal axis in a clockwise direction in Figs. 3 and 7. The throwing out of the clutch 54 will cause the switch 50 to open, thus breaking the control circuit, but the rotation of the shaft 8 and with it the cam 58 permits the switch 55 to close, thus maintaining the control circuit and holding the magnetic switch 45 closed. However the return movement of the shaft 8, that is in a counterclockwise direction, moves the cam 58 in such manner that the switch 55 is opened, thus deenergizing the solenoid 46 and allowing the magnetic switch 45 to open, a spring 59 being provided for automatically opening the switch when the solenoid is de-energized. It is evident that as soon as the

end of the beam 27 causes the impact plate 39 to retreat into its seat 40 and the clutch 54 is thrown in, the motor 16 will be started to rock the shaft 8 first clockwise to raise the stop member 18 into its retracted position and then counterclockwise to return the shaft into its position of rest.

I provide means for preventing the return of the retracted stop member to its operative position when the shaft 8 returns to its position of rest.

Thus the half socket 19 of each of the stop members is provided with a radially disposed barrel 60 in which is slidably mounted the latch pin 61, said pin being caused to protrude from said barrel by means of the helical spring 62. As the stop member is lifted into its retracted position the latch pin 61 trails down over the front of a horizontally disposed bar 63 and then springs outwardly and latches beneath the bottom edge of said bar as shown in dotted lines in Fig. 3, thus latching the stop member 18 in its retracted position.

The bar 63 is supported by means of brackets 64 whose other ends are provided with collars which are keyed on a horizontally disposed shaft 65 journaled in split bearings 66 carried by brackets 67 mounted on the girder 6. Also keyed to the shaft 65 is an arm 68 whose other end is connected by a link 69 to the piston rod 70 of a pneumatic cylinder 71. The cylinder 71 is provided with suitable control valves of any convenient type, not shown, whereby the shaft 65 may be rocked on its longitudinal axis.

During the progress of the operation of punching a beam the stop members 18 are in turn retracted as the beam progresses along the spacing table and after the beam has been removed from the spacing table the pneumatic cylinder 71 is operated to rock the shaft 65 first in a clockwise position, thus releasing the latch pins of all the retracted stop arms and allowing the stop arms to assume their horizontal position and then in a counterclockwise position to restore the bar 63 to its normal position.

The return of the shaft 8 to its normal position of rest does not tend to restore the stop arms to their normal or operative position owing to the fact that the springs 41 automatically return the keys 29 to their retracted or inoperative position shown in Fig. 4 as soon as the pressure of the end of the beam 27 is relieved from the impact plate.

To enable the operator to properly position the various stop members 18 along the spacing table to enable the holes to be spotted in the right positions in the beam I provide a gage extending parallel to the table. Thus at 72 in Fig. 3 I indicate a gage mounted on the beam 23 and this gage may be graduated so as to determine the proper positions of the several stop members.

To enable the stop member to operate accurately in halting a beam at exactly the proper position I provide impact plates 39 of different thickness, the proper plate being mounted on the stop member so that the beam will be properly halted. Otherwise the beam would be halted at intervals dictated by the ribs on the shaft 8.

I also provide hand-operated stop members, such as illustrated at 18a in Figs. 8 and 9, the same being positioned and removed by hand. Thus when a beam is to be punched adjacent to its front end or where but a single beam is to be punched, these hand operated stops may be used. In such case the impact plate 39 and the mechanism for automatically retracting the stop is not required.

The advantages of my spacing table having a working surface comprising rollers 32 along which the beam is moved are numerous. Thus the beam is simply run off the far end of the spacing table and does not need to be lifted laterally therefrom as in the present practice.

What I claim is:—

1. In apparatus for punching beams and the like, the combination with the punch head and the spacing table of a stop member arranged to be positioned in the path of the beam on the spacing table, operative connection between the punch head and the stop member whereby the stop member is retracted from the path of the beam when the latter is punched, and means whereby said operative connection is completed by the engagement of the stop member by the beam.

2. In apparatus for punching beams and the like, the combination with the punch head and the spacing table of a plurality of stop members arranged to be positioned in spaced relation along the path of the beam on the spacing table whereby to position the beam for the different punching operations, and means whereby as each punching operation is performed the corresponding stop member is retracted from the path of the beam to permit the latter to be advanced to the next stop member.

3. In apparatus for punching beams and the like, the combination with the punch head and the spacing table of a plurality of stop members arranged to be positioned in spaced relation along the path of the beam on the spacing table whereby to position the beam for the different punching operations, means whereby as each punching operation is performed the corresponding stop member is retracted from the path of the beam to permit the latter to be advanced to the next stop member, and means whereby as each stop member is retracted it is retained in its retracted position.

4. In apparatus for punching beams and the like, the combination with the punch head and the spacing table of a plurality of

stop members arranged to be positioned in spaced relation along the path of the beam on the spacing table whereby to position the beam for the different punching operations, means whereby as each punching operation is performed the corresponding stop member is retracted from the path of the beam to permit the latter to be advanced to the next stop member, means whereby as each stop member is retracted it is retained in its retracted position, and means for releasing the stop members from their retracted positions.

5. In apparatus for punching beams and the like, the combination with the punch head and the spacing table of a stop member arranged for movement into and out of the path of the beam, means arranged to be connected to the stop member to retract the same, said means being actuated when a punching operation is performed, and means whereby when the beam engages the stop member the latter is operatively connected to said retracting means.

6. In apparatus for punching beams and the like, the combination with the punch head and the spacing table of a stop member arranged for movement into and out of the path of the beam, means arranged to be connected to the stop member to retract the same, said means being actuated when a punching operation is performed, means whereby when the beam engages the stop member the latter is operatively connected to said retracting means, and means for preventing the accidental release of the retracted stop member.

7. In apparatus for punching beams and the like, the combination with the punch head and the spacing table of a plurality of stop members arranged to be positioned in spaced relation along the path of the beam on the spacing table whereby to position the beam for the different punching operations, said stop members being arranged for movement into and out of the path of the beam, means arranged to be connected with the individual stop members to retract the latter out of the path of the beam, said retracting means being actuated when a punching operation is performed, and means whereby when the beam engages one of the stop members the latter is operatively connected to the retracting means.

8. In apparatus for punching beams and the like, the combination with the punch head and the spacing table of a plurality of stop members arranged to be positioned in spaced relation along the path of the beam on the spacing table whereby to position the beam for the different punching operations, said stop members being arranged for movement into and out of the path of the beam, means arranged to be connected with the individual stop members to retract the latter out of the path of the beam, said retracting means being

actuated when a punching operation is performed, means whereby when the beam engages one of the stop members the latter is operatively connected to the retracting means, and means for holding the individual stop members retracted.

9. In apparatus for punching beams and the like, the combination with the punch head and the spacing table of a plurality of stop members arranged to be positioned in spaced relation along the path of the beam on the spacing table whereby to position the beam for the different punching operations, said stop members being arranged for movement into and out of the path of the beam, means arranged to be connected with the individual stop members to retract the latter out of the path of the beam, said retracting means being actuated when a punching operation is performed, means whereby when the beam engages one of the stop members the latter is operatively connected to the retracting means, and means for releasing the retracted stop members.

25 10. In apparatus for punching beams and the like, the combination with the punch head and the spacing table of a plurality of stop members arranged to be positioned in spaced relation along the path of the beam on the spacing table whereby to position the beam for the different punching operations, an element arranged for oscillation, means whereby said element is oscillated when a punching operation is performed, and means whereby when a stop member is engaged by the beam it is operatively connected to the element and is retracted out of the path of the beam by the movement thereof.

40 11. In apparatus for punching beams and the like, the combination with the punch head and the spacing table of a plurality of stop members arranged to be positioned in spaced relation along the path of the beam on the spacing table whereby to position the beam for the different punching operations, an element arranged for oscillation, means whereby said element is oscillated when a punching operation is performed, means whereby when a stop member is engaged by the beam it is operatively connected to the element and is retracted out of the path of the beam by the movement of the oscillating element, and means for retaining the stop member retracted.

55 12. In apparatus for punching beams and the like, the combination with the punch head, of a spacing table provided with a plurality of rollers, stop members arranged to be placed in the path of the beam along the spacing table, and means whereby when the front end of the beam engages a stop member and the punch is operated, the stop member is retracted from the path of the beam.

Signed at Pittsburgh, Pa., this 14th day of November, 1930.

65 ROBERT H. MCCLINTIC.
